[57] CLAIM

The ornamental design for a golf club head, as shown and described.

DESCRIPTION

FIG. 1 is an elevational view showing the rear face of the golf club head showing my new design,
FIG. 2 is a perspective view thereof, and
FIG. 3 is a top plan view thereof.

The front face and the bottom of the golf club head are substantially plain.

The characteristic feature of the golf club head is the continuous arcuate shape of the back and top portions of the golf club head and the wide central stripe cross wise of said arcuate shape.
